UNITED STATES PATENT OFFICE.

STEPHEN R. WARREN, OF DAYTON, OHIO.

AIR SCOOP.

Application filed April 30, 1923. Serial No. 635,628

This invention relates to air scoops for dirigibles, airships and lighter-than-air craft in general. The object of the invention is to produce a simple, effective and reliable air scoop by means of which the amount of air admitted to the balloonets of an aerostat, for example, is capable of being regulated and insured.

A further object of the invention is to so construct the air scoop as a whole, that head resistance will be reduced to a minimum, the scoop forwardly pressed in relation to its mounting upon the aerostat and the maneuverability of the air scoop insured to an extent which will prevent any tendency of the same to bind when swung laterally so as to position the mouth of the air scoop in the slipstream of either of a pair of propellers.

20 A further object of the invention is to so design the hood or shutter at the intake end of the air scoop that all tendency of said hood to chatter will be eliminated; furthermore, the hood is at all times visible, as 25 also the operating means for swinging the intake end of the air scoop laterally.

With the above and other objects in view, the invention consists in the novel construction, combination and arrangement herein 30 fully described, shown and claimed.

In the accompanying drawings—

Figure 1 is a side elevation of a dirigible showing the relation of the improved air scoop thereto;

35 Figure 2 is an enlarged side elevation of the air scoop;

Figure 3 is a front elevation of the same.

The air scoop comprises a fixed section 5 and a movable and relatively rotatable section 6, the latter being inclined downwardly and forwardly an angle of approximately 45° and being connected to the fixed section 5 by an annular ball bearing joint 7. The scoop section 6 is thus hinged to the aerostat 40 on a horizontal longitudinal axis which permits the lower and forward end of the scoop to be swung laterally. The fixed section 6 is of elbow formation 7 and fixedly secured to the aerostat.

50 The air tube or scoop section 6 is formed at its intake end with a spherical head 8 having the forward portion thereof cut away on the line 9 to form a substantially hemispherical intake mouth the latter being adapted to be covered and uncovered by means of a correspondingly shaped hood or shutter 10

thereby eliminating head resistance and also eliminating tendency of the hood or shutter to chatter when the machine is in flight and while said hood or shutter is in the slipstream of the propeller operating in advance thereof.

In order to provide for operating, that is opening or closing the hood 10, the latter is mounted on a transverse horizontal drum shaft 11 journaled in the head 8 and having fast thereon within the head 8 a drum 12 around which a flexible cable 13 is wrapped one or more times. The end portions of said flexible operating cable pass upwardly 70 around suitable guide pulleys to an operating shaft or drum convenient to the navigator. A streamline casing 14 may inclose the operating cable, as shown.

The forward end of the tube 6 is braced 73 by stiffening members 15 and 16, the member 16 being mounted in bearings 17 and 18 secured to the aerostat and having a downwardly extending right angular front portion 19 to which the stiffening member 15 is secured by a pivot or hinge pin 20 which will permit the lower stiffening member 15 to swing laterally in either direction. It is to be noted that the hinge pin 20 is in direct line with the center of the hinged joint 7 85 between the fixed and movable sections of the air scoops so that there is no tendency to bind when the air scoop is swung laterally. The pivot joint 20 is braced by means of a stay wire 21 which extends therefrom upwardly and laterally and is connected to fittings 22 on the bottom of the aerostat. The means for swinging the air scoop laterally is shown as comprising cables 23 which are fastened to the stiffener 15 just above the 90 head 8 of the air scoop, said cables extending upwardly and laterally through guides or fairleads 24 to a suitable operating drum arranged conveniently for the navigator. If desired, the drum 12 and its shaft 11 may be 100 placed in a streamline housing 25 extending transversely across within the head 8 of the air scoop.

From the foregoing description taken in connection with the accompanying drawings, 105 it will now be seen that the intake end of the scoop may be swung laterally into position behind either of a pair of propellers. The single propeller dirigible is now little used, it being the practice at the present time 110 to employ two or more propellers arranged at opposite sides of longitudinal axis of the

- aerostat and beneath the same. The scoop of a small ship is usually arranged centrally under the envelope and therefore under the present invention the intake end of the air scoop may be swung laterally so as to occupy a position behind either of the propellers and in the slipstream thereof. The spherical hood or shutter will not chatter on account of the streamline formation thereof, and, furthermore, it is at all times visible. The adjusting mechanism is simple embodying only a grooved drum or wall and a single operating cable and these will usually be enclosed with a streamline housing. Furthermore, the operating mechanism eliminates any parts which will be apt by reason of clicking or snapping to cause a spark which might ignite the gas in the aerostat, if inflammable gas be the buoyancy medium.
- 20 I claim—
1. An air scoop for dirigibles or the like embodying an air tube, a visible hood for closing and opening the intake mouth thereof, and means permitting said tube to be swung laterally to move the intake mouth thereof into and out of the propeller slip stream.
  2. An air scoop for dirigibles or the like embodying an air tube, a visible hood for closing and opening the intake mouth thereof, a partly inclosable manually operable cable for opening and closing said hood, and means permitting said tube to be swung laterally to move the intake mouth thereof into and out of the propeller slip stream, the plane of rotation of the intake mouth being

maintained parallel to the plane of rotation of the propellers.

3. In combination with a dirigible or the like, an air scoop embodying an air tube having a spherical intake head, a visible hood of corresponding shape journaled thereon to control the size of the opening in the intake head, and manually operable and partly inclosable means including a cable for shifting said hood.

4. In combination with a dirigible or the like, an air scoop embodying an air tube comprising a fixed section and a movable section hinged for lateral swinging movement having a spherical intake head, a visible hood of corresponding shape journaled thereon to control the size of the opening in the intake head, stiffening members for said tube embodying a hinge in line with the hinge joint between the sections of the air tube, and manually operable and partly inclosable means including a cable for shifting said hood.

5. In combination with a dirigible or the like, an air scoop embodying an air tube having a streamlined intake head, a visible hood journaled thereon to assure the operator of its working conditions and to control the size of the opening in the intake head, manually operable means for swinging said air tube laterally into and out of the slip stream of one or more propellers, and manually operable and partly inclosable means including a cable for shifting said hood.

In testimony whereof I affix my signature.

STEPHEN R. WARREN.
